CIRCUIT BREAKER

Joseph A. Coy, Cincinnati, Ohio, assignor to The Wadsworth Electric Manufacturing Company, Inc., Covington, Ky., a corporation of Kentucky

Application October 17, 1940, Serial No. 361,611

10 Claims. (Cl. 200—107)

The present invention relates to circuit breakers.

An object of the invention is to provide a circuit breaker which is responsive to extremely small current variations in the circuit which is protected thereby.

Another object of the invention is to provide a breaker which is adaptable to a great number of electrical wiring systems without requiring a structural change.

A further object of the invention is to provide a circuit breaker which is responsive to current conditions in either leg of a circuit protected by said breaker, or which may be made responsive to current conditions in a plurality of circuits protected by the breaker. In the latter case an overload condition in any one circuit protected by the breaker will cause said breaker to rupture all of said protected circuits.

A still further object of the invention is to provide a novel actuating member for a circuit breaker which is adapted to control and coordinate the movement of a plurality of circuit contact bridges.

Another object of the invention is to provide a number of circuit responsive devices, interposed in one or both legs of a circuit which are linked together for coordinated movement so that upon actuation of one or more of said devices, all said devices move to automatically open the protected circuit or circuits.

Another object of the invention is to provide a simple, efficient and compact circuit breaker for accomplishing the above objects.

Other objects will be apparent from the following specification and drawings, in which:

Fig. 1 is a perspective view of my circuit breaker.

Fig. 2 is an enlarged cross-sectional view taken on line 2—2 of Fig. 1.

Fig. 3 is an enlarged cross-sectional view taken on line 3—3 of Fig. 2.

Fig. 4 is an enlarged, cross-sectional view taken through the longitudinal center of the circuit breaker.

Fig. 5 is a side elevational view of the breaker with the front side wall removed.

Fig. 6 is a fragmental cross-sectional view taken on line 6—6 of Fig. 5.

Fig. 7 is a fragmental side elevational view of a modified means for actuating the collapsible means by the opposed solenoids for the breaker illustrated in Figs. 1—6.

Fig. 8 is a view taken on line 8—8 of Fig. 7.

Fig. 9 is a side elevational view of a modifica-

tion of my breaker with the cover and sides of the casing removed.

Fig. 10 is a view taken of line 10—10 of Fig. 9.

Fig. 11 is a modification of the breaker illustrated in Figs. 9 and 10.

Fig. 12 is a view taken on line 12—12 of Fig. 11.

One embodiment of my invention is illustrated in Figs. 1 to 6 and comprises a casing having a base 15 made of electrical insulating material. The base is substantially rectangular in plan view and is provided at each end with centrally disposed exterior recesses 16 and 17, said base having perforated fastening projections 18 extending therefrom and disposed at the bottom of the recesses. The casing also has a cover 19 which rests upon the base 15 and consists of a top 20 and end walls 21 and 22, said end walls being provided with recesses 23 and 24 in vertical alignment with the recesses 16 and 17 respectively, formed in the base. The cover 19 is secured to the base by means of a rear side wall 25 and a front side wall 26 which completes the casing member and engages the front and rear edges of the cover 19 and is in contact with the front and rear sides of the base 15, a plurality of transverse rivets 27 being provided to fasten the cover and the base to the front and rear side walls. The cover is also provided with cut-out portions 28 at the four corners thereof so as to expose the four corners of the base upon which the terminals of the conducting strips rest. As shown in Fig. 1, the manual switch lever and binding post terminals are the only breaker mechanism which appear exteriorly of the casing.

As shown in Figs. 2, 3 and 4, the base is provided with upstanding end projections 29 and 30 which are connected by means of a centrally disposed platform 31 extending longitudinally of the base in longitudinal alignment with recess portions 16 and 17 of said base.

Devices responsive to current conditions in the circuit take the form of solenoids 32 and 33 which are mounted in adjacent relationship on the base by means of U-shaped frames 34. The frames rest in transverse depressions 35 formed in the platform and are fastened to said base by means of screws 36 countersunk in the base (Fig. 4). Insulating material 37 is interposed between the solenoid coils and the frames whilst the exterior of said frames is electrically insulated by sheet material 38.

As shown in Figs. 2 and 3, one end 39 of the coil of solenoid 32 is fastened to conductor strip 40 which has a screw 41 at its exposed end which

serves as a binding post for one leg of a circuit to be protected. The other end of the solenoid coil is fastened to a conducting strip 42 which carries at its free end a contact 43. Another contact 44 is positioned adjacent contact 43 and said contacts constitute a pair of contacts forming a gap in the leg of the circuit in which they are interposed. Contact 44 is fastened to the free end of a conductor strip 45 which terminates exteriorly of the casing and at that end is provided with a screw 46 which is a binding post for the leg of said circuit.

Another leg of a circuit passes through the opposed longitudinal side of the base in a similar but reverse manner. As shown in Figs. 2 and 4, the circuit responsive device for solenoid 33 has one end of its coil fastened to a conductor strip 47 provided with an exposed binding screw 48, whilst the other end of the coil is fastened to a conductor strip 49 provided at its inner end with a contact 50. Contact 51, constituting with contact 50 a pair of stationary contacts, is fastened to the end of conductor strip 52 provided at its exposed end with a binding screw 53. The pairs of stationary contacts 43-44 and 50-51 are closed by means of movable contact bridges 54 and 55, respectively, which are in vertical alignment with said stationary contacts and are provided, when actuated, with a vertical rectilinear movement.

When the contact bridges are in closed contact position, the electrical circuit through the breaker is as follows:

A wire serving as one leg of a circuit is fastened to the binding post 41 and current passes through conductor strip 40, solenoid coil 32, conductor strip 42, contact 43, bridge 54, contact 44, conductor strip 45, binding screw 46; another leg of a circuit engages the conductor strip 47, the current passing through solenoid 33, conductor strip 49, contact 50, bridge 55, contact 51, conductor strip 52. The two circuits through the circuit breaker, outlined above, may constitute both legs of a circuit leading to a translator device, in which case the binding screws 41 and 53 would be fastened to the line side of said legs, whilst the binding screws 46 and 48 would be fastened to the load side of the circuit serving said device. The breaker may also be used to protect two separate circuits by wiring one leg of each circuit through one side of the breaker. The breaker may also be used for three-phase circuits, as may readily be understood by those skilled in the art.

A strip of insulating board 540 is positioned upon the conductor strips for each side of the breaker, said insulating material extending from the bottom edges of the insulating material 33 and covering the transverse area from the platform 31 to the side walls of the casing. The insulating board is provided with a cut-out portion 541 which permits the pairs of stationary contacts to extend upwardly therefrom for contact with the movable bridges 54.

The actuating means for coordinating the movement of the plurality of bridges consists of a cylindrical hollow block 56 which moves in a well 57 formed centrally in the platform 31 of the base. It will be noted that the block is guided in the well for rectilinear, axial movement, said well being positioned so that the axis of the block is centered with respect to the pairs of stationary contacts. As shown in Figs. 2, 3 and 5, the block is provided with horizontal arms 58 and 59 which are preferably made integral

with the block and which extend diametrically from the side of the block and are positioned in a vertical plane disposed intermediate two contacts constituting the pair of stationary contacts. The arms are adapted to move in open-topped slots formed in the platform, as indicated at 60 in Figs. 3 and 6. The ends of the arms are received in vertical guides 61 and 62 formed in the rear and front side walls of the casing, respectively (Figs. 1 and 2). The upper extremity of these guides limits the upper or open contact position of the actuating means which also determines the open contact position of the bridges 54 and 55 which are mounted transversely on the end portions of the arms. The cylindrical block has a web 63 formed horizontally across the interior thereof, the web being provided with a central aperture for receiving a rod 64.

The means for biasing the actuating means to open contact position comprises a coil spring 65 which encircles the lower end of the rod 64 and bears against the bottom surface of the web 63 and the bottom of the well 57. The block is moved to circuit closed position against the action of the spring 65 by means of a resilient connection between the rod 64 and the block, said connection comprising a shoulder 66 formed at the upper end of the rod and a coil spring 67 which encircles the rod and bears against the upper surface of the web and the shoulder 66.

A manual operating means is provided for controlling the movement of the actuating means which takes the form of a lever 68 having a circular body portion and rotatably mounted on the casing by means of a pin 69 which is journaled at its ends in spaced ears 70 depending from the top of the casing cover 19. As shown in Fig. 4, the circular portion of the lever has a hollow annular center 71 and a slot 72 formed in the rim of the circular portion to provide clearance for the collapsible means.

The collapsible means connecting the said operating means to the actuating means comprises a toggle element having a link 73 pivoted to the operating means by pin 74 and at its lower end pivotally fastened to a link 75 by means of a pin 76. The link 75 is U-shaped in plan (Fig. 6) at its upper end to form a shoulder 76 which, when engaged by link 73, places the links 73 and 75 over dead center with respect to their connections with the operating means and the actuating means. The lower end of link 75 is connected to the shoulder portion 76 of the rod 64 by means of a pin 77. As shown in Fig. 4, a coil spring 78 has one of its arms 79 extending into the body portion of the operating means, whilst the other arm 80 extends downwardly and is fastened to the shoulder 76 of link 75. The tendency of this spring is to constantly urge the operating means clockwise to open circuit position (Fig. 4) whilst urging the toggle element to over center position. The slot 81 formed in the top of the casing serves as a stop for limiting the positions of the manually operating means.

The armatures 82 and 83 for the solenoids 31 and 33, respectively, are fastened together by means of a bar 84, said bar being connected to cut-out portions in said armatures by means of screws 85. The means on the bar for engaging the collapsible means at its jointed portion 76 comprises a lug 86. The collapsible means, as shown in Fig. 6, is in the path of movement of the lug 86 when the solenoid is actuated. The armatures of the solenoids are biased to the position indicated in Figs. 1 to 6 by means of a compres-

sion spring 87 which bears against the end wall of the casing cover and the armature 82, the stop for said armatures being the side of the casing cover against which the armature 83 is urged.

A sheet of insulating material 870 having an inverted U-shaped form encloses the collapsible means and is provided with openings 871 in the vertical side walls thereof to allow the armatures of the solenoids and the bar 84 connecting them to pass therethrough. The lower ends of the vertical sides of the material are in contact with the top and sides of the platform 31 and also the transverse portion of the insulating material 540. As shown in Fig. 6, insulating panels 872 are positioned against the side walls of the casing and are adapted to close off the longitudinal edges of the U-shaped insulating material 870.

In operation, when an overload condition occurs in one or both of the circuit legs in which solenoids 32 or 33 are interposed, the armatures 82 and 83 will center themselves with respect to the solenoid coils against the action of the compression spring 87 and thus move the lug 86 to a position indicated by dotted lines in Fig. 4. In this position lug 86 will collapse and thereby render ineffectual the toggle element of the collapsible means, thus throwing the operating means, the actuating means and the collapsible means to a position indicated in dotted lines in Fig. 4. The latter position is taken by the parts to the position indicated in Fig. 4 after actuation of the lug 86 because, as soon as the toggle joint is broken, spring 78 moves the manually operating means clockwise to its dotted line position while the spring 65 in the well moves the block 56 upwardly to its dotted line position to open the circuit. The lower arm 80 of the spring 78 tends to urge the toggle joint after it has been broken to its straight line over center position and said joint will therefore take up that position indicated in dotted lines in Fig. 4. To reset the breaker, it is only necessary to move the operating means from its dotted line position to the full line position shown in Fig. 4.

I also contemplate modifying my breaker so that the armatures of the circuit responsive devices 32 and 33 may independently actuate the collapsible means to open either circuit leg running through my breaker. In this respect, Figs. 7 and 8 illustrate a form of the modification (like numerals refer to similar parts in the drawings) wherein armature 82 of the solenoid 32 is provided with a short bar 88 having a flat shelf-like portion 89 formed at its outer end at right angles to said bar in longitudinal alignment with the toggle joint of the collapsible means. A vertical support 90 extends upwardly from the base 15 and slidably engages the under side of the shelf 89. The armature 83 of the solenoid 33 has a short bar 91 connected thereto which at its outer end is provided with a right-angled shoulder portion 92 which rests on the shelf 89. A compression spring 87 for urging the armature 82 to the righthand side of Fig. 7 is provided while tension spring 93 biases the armature 83 in a direction to the right in said figure. It will therefore be seen that upon actuation of the armature 82 or armature 83, they will move against the action of the springs associated therewith to independently trip the toggle joint and open both circuit legs running through the breaker illustrated in Figs. 1-6, inclusive.

In Figs. 9 and 10 there is illustrated a modification of my breaker employing a bi-metal instead of a solenoid as the means responsive to

current conditions in a circuit. In this form the base and the casing therefore remain substantially the same as the base shown in Figs. 1 to 7, inclusive. (Like reference numerals refer to similar parts.) Conductor strip 94 has a binding screw 95 at one end and has one of a pair of stationary contacts 96 at its other end. The strip is fastened to the base 15 by means of a screw 97. The other stationary contact, constituting the pair, is indicated by numeral 98, said contact being fastened at the end of a conductor strip 99, which contact is fastened to the base by a screw 100. This conductor strip 99 is in electrical contact with a foot portion of an inverted U-shaped bi-metal element 101 while the free leg of the bi-metal element is electrically connected to a conducting strip 102 having a binding screw 103 at its outer end. As illustrated, the electrical contact for the legs of the bi-metal elements are screws 104 which are threaded through the strips and the feet portions of the bi-metal element and into the base 15. The other leg of a circuit through the breaker is similar to that just described and consists of a conducting strip 105 provided at its inner end with a stationary contact. A strip 106 is also provided with a stationary contact which constitutes a pair of stationary contacts and is electrically connected to one leg of an inverted U-shaped bi-metal element 107 by means of a screw 108. The other foot of the bi-metal is connected to a conductor strip 109 by means of a screw 110.

The upper ends of the bi-metal elements are connected by a rectangular frame 111, the opposed parallel sides of the frame being connected to the bi-metal elements by means of rivets 112. A transverse rod 113 supported by opposite longitudinal sides of the frame is positioned in alignment with the toggle joint between the links 73 and 75 and is adapted to be moved toward said joint when overload conditions in either or both circuit legs through the breaker deflect the bi-metal elements. This movement of the rod 113 toward the toggle joint moves said joint beyond dead center thereby collapsing said joint and permitting the bridges 54 and 55 to move upwardly under the control of the actuating means located in the well 57 of the platform 31. The structure of the actuating means is similar to that shown in Figs. 1 to 6.

Figs. 11 and 12 show a modification of the bi-metal circuit responsive means shown in Figs. 9 and 10. (Reference numerals used indicate similar parts.) The structure in Figs. 11 and 12 is similar to that in Figs. 9 and 10, except that the means connecting the upper ends of the bimets 101 and 107 is modified so that each bi-metal may act independently of the movement of the other upon the toggle joint. In this respect, bi-metal 107 is provided with a U-shaped frame 114 which is fastened at its transverse portion 115 to the upper end of the bi-metal by means of a screw 116. The ends of the link portions of said frame are turned at right angles inwardly, said portion 117 upon deflection of the bi-metal engaging the toggle joint, whilst the other portion 118 of the frame is provided with an aperture 119 therein for receiving the free end of a rod 120 fastened by screw 121 to the upper end of bi-metal 101. The free end of the rod 120 is in a longitudinal position to contact the toggle joint when bi-metal 121 is deflected. It will therefore be understood that either bi-metal 107 or 101 may independently break the

toggle joint, thus opening both circuit legs running through the breaker.

What is claimed is:

1. In a circuit breaker the combination of a base, a number of pairs of stationary contacts on the base, a contact bridge for engaging each pair of stationary contacts, and adapted to engage and disengage said stationary contacts, a well formed in the base and disposed between the pairs of stationary contacts, an actuating means comprising a cylindrical block guided for rectilinear, axial movement in the well, horizontal arms extending diametrically from the side of the block and positioned in a vertical plane disposed intermediate two contacts constituting a pair of stationary contacts, and a horizontal contact bridge extending transversely from the end portion of each arm and in vertical alignment with a pair of stationary contacts, means for biasing the actuating means to contact disengaged position, a manually operating means, a collapsible means connected to the operating means and resiliently engaging the block, and normally adapted to hold the actuating means in contact engaged position, and means responsive to current conditions in the circuit for acting on the collapsible means and rendering said means ineffective to hold the actuating means in contact engaged position.

2. In a circuit breaker the combination of a base, a casing having a top and side walls fastened to the base, a number of pairs of stationary contacts on the base, a contact bridge for engaging each pair of stationary contacts, and adapted to engage and disengage the stationary contacts, a well formed in the base and disposed between the pairs of stationary contacts, an actuating means comprising a cylindrical block guided for rectilinear, axial movement in the well, horizontal arms extending diametrically from the side of the block and positioned in a vertical plane disposed intermediate two contacts constituting a pair of stationary contacts, and a horizontal contact bridge extending transversely from the end portion of each arm and in vertical alignment with a pair of stationary contacts, vertical guides in opposed side walls of the casing for receiving the ends of the arms, said guides acting as stops for determining the contact disengaged position of the actuating means, means for biasing the actuating means to contact disengaged position, a manually operating means, a collapsible means connected to the operating means and resiliently engaging the block, and normally adapted to hold the actuating means in contact engaged position, and means responsive to current conditions in the circuit for acting on the collapsible means and rendering said means ineffective to hold the actuating means in contact engaged position whereby said actuating means is moved under the influence of its bias to contact disengaged position.

3. A circuit breaker, as set forth in claim 2, wherein the resilient connection between the block and the collapsible means constitutes a hollow block, a rod fastened to the collapsible means and disposed axially through the block, said rod having a shoulder thereon, a web portion extending across the interior of the block and having an aperture centrally therein for receiving the rod, and coil spring encircling the rod and engaging the shoulder and the web.

4. A circuit breaker, as set forth in claim 2, wherein the means for biasing the actuating means to contact disengaged position comprises

a hollow cylindrical block provided interiorly with a web portion, and a coil spring disposed within the block and bearing against the bottom of the well and the web portion of the block.

5. In a circuit breaker the combination of a base, circuit responsive devices mounted in adjacent relationship on the base, each responsive device adapted to be interposed in a leg of a circuit, pairs of stationary contacts mounted on the base and each pair adapted to be in a leg of a circuit, movable contact bridges each adapted to engage and disengage a pair of stationary contacts, a collapsible means engaging the contact bridges and positioned between the circuit responsive devices for holding said bridges in contact engaged positions, means for biasing the collapsible means to contact disengaged position, and means fastened to the movable part of each circuit responsive device for tripping the collapsible means when an overload occurs in a leg of a circuit in which said device is interposed to thereby render the collapsible means ineffective to hold the bridges in contact engaged positions thus permitting all of said bridges to move under the influence of the biasing means to contact disengaged positions.

6. In a circuit breaker the combination of a base, circuit responsive devices mounted in adjacent relationship on the base, each responsive device adapted to be interposed in a leg of a circuit, pairs of spaced, stationary contacts mounted on the base and each adapted to be in a leg of a circuit, a movable contact bridge adapted to engage and disengage each pair of stationary contacts, collapsible means engaging the contact bridges and positioned between the circuit responsive devices for holding said bridges in contact engaged positions, means for biasing the collapsible means to contact disengaged position, and an arm fastened to the movable part of each of the circuit responsive devices for tripping the collapsible means when an overload occurs in a leg of a circuit in which a circuit responsive device is interposed to thereby render the collapsible means ineffective to hold the bridges in contact engaged positions thus permitting all of said bridges to move under the influence of the biasing means to contact disengaged positions.

7. In a circuit breaker the combination of a base, circuit responsive devices mounted in adjacent relationship on the base, each responsive device adapted to be interposed in a leg of a circuit, pairs of spaced, stationary contacts mounted on the base and each pair adapted to be in a leg of a circuit, movable contact bridges adapted to engage and disengage the pairs of stationary contacts, collapsible means engaging the contact bridges and positioned between the circuit responsive devices for holding said bridges in contact engaged positions, means for biasing the collapsible means to contact disengaged position, a bar fastened to the movable part of the circuit responsive devices, and means on the bar for tripping the collapsible means when an overload occurs in a leg of a circuit in which a circuit responsive device is interposed to thereby render the collapsible means ineffective to hold the bridges in contact engaged positions thus permitting all of said bridges to move under the influence of the biasing means to contact disengaged positions.

8. In a circuit breaker the combination of a base, circuit responsive devices mounted in adjacent relationship on the base, each responsive device adapted to be interposed in a leg of a cir-

cuit, pairs of spaced, stationary contacts mounted on the base and each pair adapted to be in a leg of a circuit, movable contact bridges adapted to engage and disengage the pairs of stationary contacts, collapsible means engaging the contact bridges and positioned between the circuit responsive devices for holding said bridges in contact engaged positions, means for biasing the collapsible means to contact disengaged position, a linking member fastened to the movable part of each circuit responsive device, and a lug on the member for tripping the collapsible means when an overload occurs in a leg of a circuit in which a circuit responsive device is interposed to thereby render the collapsible means ineffective to hold the bridges in contact engaged positions thus permitting all of said bridges to move under the influence of the biasing means to contact disengaged positions.

9. In a circuit breaker the combination of a base, circuit responsive devices mounted in adjacent relationship on the base, each responsive device adapted to be interposed in a leg of a circuit, a linking member fastened to the movable part of each circuit responsive device for coordinating the movement of said devices in a common plane, a collapsible means positioned adjacent the linking member and intermediate the devices, arms extending from the collapsible means at right angles to the plane of movement of the linking member, pairs of spaced, stationary contacts mounted on the base and each pair adapted to be in a leg of a circuit, a contact bridge fastened centrally on each arm and adapted to engage and disengage a pair of stationary contacts, means for biasing the collapsible means to contact disengaged position, an operating means for holding the collapsible means in contact engaged position against the action

of the biasing means, and means on the linking member for tripping the collapsible means when an overload occurs in a leg of a circuit to thereby render the collapsible means ineffective to hold the bridges in contact engaged positions thus permitting all of said bridges to move under the influence of the biasing means to their contact disengaged positions.

10. In a circuit breaker the combination of a base, circuit responsive devices mounted in adjacent relationship on the base, each responsive device adapted to be interposed in a leg of a circuit, a linking member fastened to the movable part of each circuit responsive device for coordinating the movement of said devices in a common plane, a collapsible means positioned adjacent the linking member and intermediate the devices, arms extending from the collapsible means at right angles to the plane of movement of the linking member, pairs of spaced, stationary contacts mounted on the base and each pair adapted to be in a leg of a circuit, a contact bridge fastened centrally on each arm and adapted to engage and disengage a pair of stationary contacts, means for biasing the collapsible means to contact disengaged position, an operating means for holding the collapsible means in contact engaged position against the action of the biasing means, means for biasing the operating means to contact disengaged position, and means on the linking member for tripping the collapsible means when an overload occurs in a leg of a circuit to thereby render the collapsible means ineffective to hold the bridges in contact engaged positions thus permitting all of said bridges and the operating means to move under the influence of their respective biasing means to contact disengaged positions.

JOSEPH A. COY.
